(57) **CLAIM**

The ornamental design for a safety cap for a bottle, as shown and described.

DESCRIPTION

FIG. 1 is a top perspective view of the safety cap for a bottle; FIG. 2 is a top plan view of the safety cap for a bottle shown in FIG. 1;

FIG. 3 is a bottom plan view of the safety cap for a bottle shown in FIG. 1;

FIG. 4 is a front end view of the safety cap for a bottle shown in FIG. 1;

FIG. 5 is a back end view of the safety cap for a bottle shown in FIG. 1;

FIG. 6 is a side view of the safety cap for a bottle shown in FIG. 1; and,

FIG. 7 is an opposite side view of the safety cap for a bottle shown in FIG. 1.

The broken lines and unshaded areas in the drawings depict portions of the safety cap for a bottle that form no part of the claimed design.

1 Claim, 4 Drawing Sheets
